MATERIAL HANDLING DEVICE

George J. Hulbert, Seattle, Wash.

Application August 6, 1945, Serial No. 609,103

3 Claims. (Cl. 212—8)

1

This invention relates to material handling devices.

An object of this invention is to provide a material handling device that is particularly well adapted for use in building construction to deliver building material to a location where it is to be used.

Another object of this invention is to provide a material handling device that can be operated by hand and that is well adapted for delivering roofing slabs onto a roof to which they are to be applied.

Another object is to provide a material handling device comprising a carriage having a boom pivoted thereto approximately mid-way between the two ends of the boom for swinging movement, and having winch operated means for hoisting or lowering a load relative to the boom.

Other objects are to provide a material handling device that is simple in construction, efficient in operation, not expensive to build and one that will make possible a saving in labor and an increase in efficiency in the application of roofs where large heavy roof panels are used.

Other objects of the invention will be apparent from the following description taken in connection with the accompanying drawings.

In the drawings Fig. 1 is a front elevation of a material handling device constructed in accordance with my invention showing a hoisting boom thereof in a generally upright position.

Fig. 2 is an end view of said device, showing by full lines the hoisting boom in a substantially upright position and by dot and dash lines said boom in an inclined position and also showing by dot and dash lines the outline of a building to which material is to be delivered by this material handling device.

Like reference numerals designate like parts throughout the several views.

This device comprises a rolling scaffold or carriage 5 mounted on wheels 6. The carriage 5 is adapted to be moved along any suitable deck or run-way 7, that is provided alongside of a building or like structure 4 to which material is to be delivered. The building 4 is shown by dot and dash lines in Fig. 2.

The carriage 5 is provided with upper and lower cross pieces 8 and 9 that project outwardly from the outermost side of said frame. Substantially upright frame members 10 are secured to the overhanging end portions of the cross pieces 8 and 9 and extend to a substantial distance above the carriage 5. The frame members 10 are slightly inclined toward the building 4 from bottom to top

2

of said members 10 for purposes hereinafter explained.

A swinging boom is composed of spaced apart longitudinal boom members 11 and suitable cross braces and angular braces 12. This swinging boom is pivotally supported by a cross shaft 13 that extends crosswise through the upper end portions of the upright frame members 10. The cross shaft or pivot member 13 is positioned substantially mid-way between the two ends of the boom members 11 so that the boom is approximately balanced on the pivot 13 as respects its weight. The lower ends of the boom members 11 are just clear of the deck 7 when the boom 15 is in a substantially upright position and the carriage is resting evenly on all four wheels 6. If the upper portion of the carriage starts to tilt away from the building 4 then the lower ends of these upright frame members 10 will engage with the deck 7 and arrest such tilting movement.

A snubbing line or rope 14 is secured to the lower end portion of the swinging boom and may be used by an operator to control the swinging movement of the boom. The loose end portion of the rope 14 may be snubbed around a suitable cross piece 29 that is rigid with the carriage.

A sheave 15 is rotatively mounted on the cross shaft 13 and another sheave 16 is rotatively mounted on another cross shaft 17 at the upper 30 end of the boom.

A winch or winding drum 18 is mounted on the carriage 5 in a convenient location for hand operation. A hauling cable 19 is wound on the winch 18 and passes upwardly over the guide sheave 15, thence around the top sheave 16 and thence downwardly along the boom. A hook 20 is provided on the lower end portion of the cable 19.

Preferably locking means such as a bolt 21 is provided for locking the swinging boom in the upright position. Also preferably the winch 18 is provided with locking means which may be used to lock the winch in any desired position. This winch locking means may be a pawl 22 adapted 45 to engage with ratchet teeth 23 on the winch 18. A crank 24 is provided on the winch 18 for manual operation of the same. One use for which this device is well suited is for delivering large sheets of roofing material 26 onto a roof 27 to which they are to be applied. These sheets 26 are relatively large, being as much as nine feet long and three feet wide. Also they are too heavy and cumbersome for one man to pick up and carry. Each sheet 26 is provided with one or more holes 55 28 to facilitate handling.

In elevating these sheets 26 of roofing with my device the swinging boom is placed in a generally upright position in which it is parallel to the frame members 10 and slightly inclined toward the building and a sheet 26 of the roofing is leaned against the lower end portion of this swinging boom, see Fig. 2. The hook 20 is engaged within a hole 28 in the roofing sheet 26 and the winch 18 is operated to elevate the sheet 26 along the boom. The sheet 26 is wide enough so that it slides on the members 11.

The boom is inclined toward the building just enough so that the upper end portion of this boom will tend to swing toward the building as soon as the major portion of the roofing sheet 26 is moved above the cross shaft 13. The shaft 13 is preferably positioned a short distance below the eave portion of the building. This makes it possible for the operator, by slackening the snubbing rope 14, to lay the upper end portion of the boom down on the roof 27 and then by further winding of the hauling line 19 on the winch 18 to draw the roofing panel or load 26 to the upper end of the boom or to any desired location where said load may be most conveniently removed.

Preferably a cross piece 25 is provided on the boom near the upper end portion thereof to rest on the roof 27 when the boom is in the inclined position.

Obviously a load may be lowered from the roof 27 by placing it on the boom, attaching the hook 20 thereto lowering the load along the boom and swinging the boom into the substantially upright position. In so lowering a load it is possible to first elevate the boom with the load thereon into an upright position and then lower the load or to slide the load down along the inclined boom until the load is approximately over the pivot shaft 13 then swing the boom into the generally upright position and complete the lowering of the load.

Oppositely extending cables 30 may be secured to the frame members 10 to help in moving the carriage 5 along the deck 7 parallel to the building 4 or to hold the carriage in a fixed position.

This device can be operated by hand for elevating material onto a roof or any other part of a building within reach of the boom 11. Also, if desired, provision can be made for using power means in the operation of the winch 18.

It is also possible to use this material handling device inside a building with the upper end portion thereof extending upwardly through a partly completed roof between the purlins or rafters thereof. To facilitate use of this device in this manner I preferably provide on the shaft 17 at the upper end of the boom 11, two or more rollers 29 over which the material that is being elevated may easily be rolled or drawn off over the top end portion of the boom. Obviously material so elevated could be discharged over the top end of the boom by pulling on the hoisting cable 19 or it could be removed by a person on the roof.

This device is simple and efficient and makes it possible for one person to elevate sheets 26 of roofing to a roof at a great saving in time and labor as compared to the usual method of carrying these sheets up onto a roof.

Obviously changes in my invention may be made within the scope and spirit of the following claims.

I claim:

1. A hoist for delivering material onto a building comprising a carriage movable along the side of a building; upright frame means rigidly se-

cured to said carriage and extending above said carriage; a boom pivotally connected intermediate its two ends with the upper end portion of said upright rigid frame and movable between a substantially upright position and a position in which the upper end portion of the boom is over the building, said boom having a relatively smooth and unobstructed outer face capable of supporting a load for sliding movement along the boom, the length of the portion of said boom below the pivot thereof being approximately equal to the distance between the pivot and the bottom of the carriage whereby the bottom end portion of said boom will be clear of the surface on which the carriage is supported when the boom is in a substantially upright position; a sheave carried by the upper end portion of said boom; another sheave coaxial with the pivot of said boom; a hoisting cable operable over said sheaves adapted to have one end portion connected with a load that is positioned against the outer face of said boom and to have a pull exerted thereon to move a load upwardly along said boom; and a snubbing cable connected with the lower end portion of the boom for controlling the swinging movement of said boom.

2. In material handling means, a carriage; wheels supporting said carriage for movement along a runway; rigid frame means rigidly secured to said carriage and extending above said carriage at one side thereof; a boom pivoted to the upper end portion of said frame means approximately mid way between its two ends; two sheaves carried by said boom and positioned respectively adjacent the upper end of said boom and on the pivotal axis of said boom; a hoisting cable operable on said sheaves adapted to have its upper end portion connected with a load; means operable to limit the extent of pivotal movement of said boom; and a winch on said carriage, the hoisting cable being connected with said winch for operating said cable.

3. In material handling means, a carriage; rigid frame means rigidly secured to said carriage and extending above said carriage at one side thereof; a boom pivoted to the upper end portion of said frame means approximately mid way between its two ends and arranged to swing from a substantially upright position sidewise over said carriage; a snubbing cable connected with the lower end portion of said boom to limit the extent of pivotal movement of the boom; two sheaves carried by said boom and positioned respectively at the upper end portion of said boom and on the pivotal axis of said boom; a hoisting cable operable on said sheaves to lift a load upwardly along said boom, said hoisting cable being adapted to have its upper end portion connected with a load; and a winch mounted on said carriage adjacent the lower end portion of the hoisting cable having the lower end portion of the hoisting cable connected therewith for operating said hoisting cable.

GEORGE J. HULBERT.
